United States Patent Office

Des. 212,596
Patented Nov. 5, 1963

212,596

HANDLE FOR DOORS, DRAWERS, OR THE LIKE

Robert G. Plantholt, Rochester, Mich., assignor to Borg-Warner Corporation, Chicago, Ill., a corporation of Delaware

Filed Dec. 26, 1967, Ser. No. 9,906

Term of patent 14 years

(Cl. D10—8)

FIG.1

FIG.5

FIG. 1 is a perspective view of a handle for doors, drawers, or the like showing my new design;

FIG. 2 is a top view of the handle;

FIG. 3 is a front view of the handle;

FIG. 4 is a left side view of the handle; and

FIG. 5 is a right side view of the handle.

The dominant features of my design reside in the portions shown in full lines.

I claim:

The ornamental design for a handle for doors, drawers, or the like, substantially as shown and described.
